LIFT COVER FOR COOKING TOPS

Stanley H. Hobson, Rockford, Ill., assignor to
 Geo. D. Roper Corporation, Rockford, Ill., a
 corporation of Illinois

Application February 16, 1939, Serial No. 256,655

15 Claims. (Cl. 126—214)

This invention relates to a new and improved lift cover for the cooking tops of gas ranges and the like.

One of the principal objects of my invention is to provide a lift cover having self-contained counter-balancing spring means and also an adjustable stop for limiting the pivotal movement when the cover reaches a desired vertical position.

Another important object is the provision of a lift cover of sheet metal construction incorporating therein as part of the hinge means and for reinforcement of the hinge end of the lid a full length casting cooperating with cast hinge leaves adapted to be secured to the body of the range, the design being such that there is a minimum exposure of the cast parts outside of the lift cover and the cooking top, whereby the appearance of the cover and range as a whole is materially improved.

Still another object lies in the special formation and elongation of the hinge leaves which attach to the body of the range, so that there is no interference with other parts of the range equipment which extend through the rear wall of the burner box compartment where these leaves are adapted to be fastened, and so that the leaves have sufficient length of bearing contact with the sheet metal back wall to eliminate buckling of the back wall under the strain imposed thereon when the cover is raised and lowered.

A further object consists in further forming the leaves to permit quickly detaching and withdrawing the same from the range so that the cover may be removed without disassembling the hinges therefor.

It is also an important object of my invention to so construct the two sheet metal panels forming the cover that they interfit at one end and are adapted to be secured together at the other end by small unnoticeable screws entered in registering holes in the end flanges on said panels, the inner one of the panels being further specially formed at the same end where the screws are entered whereby to receive the full length hinge casting in a recess in the panel so that two bolts are sufficient to fasten the casting to the panel, the heads of said bolts being in the outside of the cover, but concealed when the cover is lowered, and being furthermore disposed in depressed portions of the inner panel so as not to be at all conspicuous when the cover is raised.

The invention is illustrated in the accompanying drawing, in which

Fig. 1 is a plan view of a portion of a gas range having lift covers for the cooking top made in accordance with my invention, one of said covers being shown lowered and the other raised, the lowered cover being broken away at one corner to indicate one of the slots in the cooking top through which the hinge leaves project, the hinge leaf appearing in section.

Fig. 2 is a section on the broken line 2—2 of Fig. 1, on a larger scale, intermediate portions of the range and cover being broken away to permit showing the parts on such an enlarged scale.

Fig. 3 is a cross section on line 3—3 of Fig. 2, and Figs. 4 to 7 are sectional details on a still further enlarged scale taken on the correspondingly numbered lines in Fig. 2.

The same reference numerals are applied to corresponding parts throughout the views.

The range herein illustrated is of the well known low oven type having the cooking top at approximately table height with the oven sections therebeneath. The present invention is concerned with lift covers 9 to be hingedly mounted with respect to the cooking top 8 and adapted when raised to expose cooking top burners like those shown at 10, and when lowered to conceal these burners so as to give the range a neater and more attractive appearance. 11 is a back rail at the rear of the cooking top, and the covers 9 are preferably hinged for pivotal movement relative to the cooking top in spaced relation to said back rail, and when raised will preferably occupy approximately vertical positions substantially parallel to the back rail as indicated in Figs. 1 and 3. While these lift covers have been especially designed for use on the type of gas ranges mentioned, it should, of course, be clear that the invention is not limited to use on that particular type but may be used wherever such covers are of advantage, and the use is furthermore not limited to gas ranges.

Each lift cover 9, in accordance with my invention, has the body thereof of hollow, sheet metal construction for lightness and cheapness, the body in each instance being formed by two nested dished panels 12 and 13, both porcelain enameled on the outside so that the cover presents a good appearance raised or lowered. The outer panel 13 has a circumferentially extending flange 14, which is cut away at two points on the inner or hinged end of the cover, as indicated at 15, to receive the upper enlarged knuckle end portions 16 of hinge leaves 17, which are pivotally connected by pintles 18 with companion knuckle portions 19 on a generally U-shaped casting 20 that

is fastened inside the inner end portion of the other panel 12 by bolts 21. The flange 14 has an in-turned edge portion 22 along the outer end of the panel 13, and this edge portion 22 enters an elongated recess 23 provided on the outer end of the panel 12 to hold the panels in nested relation without using screws or other fasteners. The recessing at 23 is just deep enough so that the edge portion 22 comes flush with the rest of the edge portion of the panel 12. There is a circumferentially extending flange 24 on the panel 12, which fits inside the circumferential flange 14 of the panel 13 fairly closely, and two small screws 25 are entered through holes 15 provided therefor in the flange 14 and thread in registering holes provided therefor in the flange 24. The screws 25 are at the inner corners of the cover, opposite the point of connection 22-23 just described, so that the panels 12 and 13 are held together securely although only two small screws are used. The fact that they are so located and so small makes them unnoticeable. Any suitable padding or filling 26 may be inserted between the panels at the time of assembling the cover to tend to spread the panels apart resiliently sufficiently to insure keeping the edge portion 22 solidly engaged in the recess 23 at all times. In that way there is avoided any likelihood of play being developed between the panels and they always swing together as a unit, like a one-piece cover. Ordinary corrugated paperboard has been found suitable for the purpose, and a single wad extending the width of the cover at a midpoint between the inner and outer ends gives the desired result. The panel 12 has the flange 24 cut away in register with the cut away portions 15 as appears in Fig. 2 to accommodate the knuckle portions 16 of the hinge leaves 17, and the panel is further cut away, as indicated at 27, to provide operating clearance for the knuckle portions 16 so that the cover can be swung downwardly to a horizontal position substantially at right angles to the vertical plane of the knuckle portions 16. The panel 12 is preferably formed with U-shaped embossed portions 28 of channel-shaped cross section defining the cut-out portions 27 whereby to reinforce the panel at those points. There are embossed corner portions 29 formed on the panel 12, which project sufficiently from the inner face 30 of the cover, as indicated in Fig. 3, to serve as feet for support of the cover in spaced relation to the cooking top when lowered.

The panel 12 is fairly deeply dished, leaving a marginal portion 30 of substantially channel-shaped cross section, one side of the channel being formed by the aforementioned circumferential flange 24. The U-shaped hinge casting 20 previously mentioned is made to fit in the channel-shaped portion 30 and, being thereby positioned with respect to the panel 12 and the cover 9 as a whole, two bolts 21 are quite sufficient to fasten the casting in place. These bolts are entered through holes 31 in recessed corner portions 32 of the panel 12 and pass through tapered holes 33 in the corner portions of the casting 20. Lock washers 34 and nuts 35 fit on the projecting ends of the bolts and when the bolts are tightened the casting is anchored securely in the cover. With the construction shown, there is no need for exact registration of the holes 31 with the holes 33, and assembling of the covers is therefore facilitated and there is no danger of chipping or cracking the porcelain enamel. The casting 20 is practically entirely concealed inside the 75 cover, only small portions of the knuckles 16

thereon being visible only when the covers are raised.

The hinge leaves 17 are likewise cast for economy in production and as indicated in Fig. 1 are of flattened cross section so as to have broader 5 engagement with the sheet metal back wall 36 of the range to which they are adapted to be secured when extended downwardly through slots 37 in the cooking top 8 into the burner box compartment 38. Bolts 39 used for fastening the 10 upper edge portion of the back wall 36 to the angle iron top frame member 40 are arranged to be entered through holes 41 in the hinge leaves 17 for fastening the same to the back wall. Nuts 42 are threaded on the projecting ends of the bolts 15 as shown. Other bolts 43 used for fastening the flanged rear edge 44 of the burner box bottom 45 to the back wall 36 are adapted to be loosened to leave enough space between the flange 44 and the nuts 46 to permit slipping the forked lower ends 47 20 of the hinge leaves 17 in between, whereupon when the bolts are tightened the hinge leaves are fastened securely at their lower ends. The fact that the hinge leaves 17 are elongated to reach the full depth of the burner box compartment 38 permits such wide spacing of the bolts 39 and 43 used for fastening the hinge leaves to the sheet metal back wall 36 that there is no danger of the sheet metal wall buckling under the strain imposed thereon when the lift cover is 30 raised or lowered. Obviously too the abutment of the hinge leaves 17 with the flanged rear edge 44 of the burner box bottom 45 makes for much greater rigidity of these hinge members. The upper enlarged knuckle portions 16 have projecting annular bead portions 48 which cover up the slots 37 in the cooking top, for good appearance. Thus the only portions of the hinges visible when the covers are raised are the knuckle portions 16. In passing it will be observed in 40 Fig. 2 that the lower end portions 49 of the two leaves 17 are both offset in the same direction and to the same extent relative to the upper end portions 50. That is to avoid interference between the hinge leaves and certain parts of the 45 range equipment in the burner box compartment 38. For example, as shown in Fig. 2, the back wall 36 has an opening 51 provided therein through which a flexible pipe connection is adapted to be extended for connecting the gas 50 supply manifold for the cooking top burners with the service pipe in the kitchen, and by having the lower end of the adjacent leaf 17 offset as shown so as to extend along the side of the opening instead of across it, there is no interference whatever with making the service connection. These offsets in the leaves 17 do not interfere at all with the easy assembling and disassembling of the covers on the range; when the two nuts 42 fastening a related pair of hinge 60 leaves 17 are removed and the lower bolts 43 are loosened, one can easily remove the cover by lifting the same to withdraw the hinge leaves 17 from the burner box compartment through the slots 37, slight lateral movement being involved 65 by reason of the offsetting of the lower end portions 49 with respect to the upper end portion 50. There is an obvious advantage in the present construction over others in that one may remove a cover without having to disassemble the hinges. 70 Removal may be found necessary occasionally due to damage of the covers in shipment or at the time of installation, due to carelessness or awkwardness in handling.

Each of the knuckle portions 16 provides a pair 75

of spaced knuckles 52 and 53 receiving therebetween a knuckle 54 of one of the knuckle portions 19 of the casting 20. The hinge pintle 18 for each hinge is extended through registering holes 5 in knuckles 52-54 and through other registering holes in lugs 55 and 56 provided in laterally spaced relation to and on opposite sides of the knuckle 54 on the casting 20. Two coiled torsion springs 57 and 58 are mounted on the pintle 18 on opposite sides of the knuckle portion 16 bearing at one end on the knuckle portion and at the other on the casting 20 to urge the cover normally toward vertical position. Thus for example, as shown in Fig. 5, the spring 58 has the one end 59 engaged behind a lateral projection 60 on the knuckle 53, and the same is true for the adjacent end of the spring 57 which cooperates with a lateral projection 60 on the knuckle 52. The other ends 61 of the springs, for example the end 61 of the spring 57 shown in Fig. 6, bear against the front of the casting 20 in recesses 62 provided therefor. The four springs, there being two associated with each of the hinges, serve to counter-balance the cover so that it cannot drop onto the cooking top and result in any damage or injury, but as a matter of fact will remain stationary in practically any intermediate position to which it may happen to be moved. When the cover nears vertical position where its weight is mainly downwardly on the pintles 18 and there is no lateral component, the springs 57 and 58, even though partially unwound under these conditions, exert sufficient force to tend to swing the cover past dead center in the direction of the back rail 11, and it is therefore necessary to provide a stop to limit pivotal movement of the cover when in raised position. For that purpose I provide two set screws 63, one on each of the knuckles 54 of the casting 20, arranged to engage lateral projections 64 provided on the knuckles 52. One of these screws 63 is first adjusted so that the cover stands substantially vertical when swung back as far as it will go, and then the other screw 63 is turned until it encounters its related projection 64, thus distributing the load on two projections and avoiding the likelihood of breakage. It is obvious that the present construction provides the counter-balancing means and the stop adjustment as a part of the cover assembly and due to the compactness and concealment of parts between the two panels forming the cover, the resulting structure presents an unusually neat and attractive appearance and the housewife has no difficulty in keeping the range clean.

It is believed the foregoing description conveys a good understanding of the objects and advantages of my invention. The appended claims have been drawn with a view to conveying all legitimate modifications and adaptations.

I claim:

1. In a range construction, the combination of a cooking top, a frame member therebeneath and in rigid relation thereto, a sheet metal burner box bottom in downwardly spaced relation to the frame member and having an upwardly projecting rear flange, a vertical sheet metal back wall adapted to be secured to said frame member and burner box bottom in rigid relation to the cooking top, bolts entered through the frame member and the upper edge portion of the back wall for securing the same together, other bolts entered through the back wall and the rear flange on the burner box bottom for securing the same together, a lift cover adapted to be hingedly

mounted on the range over the cooking top, and hinge means therefor including substantially vertical attaching members entered through slots provided therefor in the cooking top adjacent the back wall, and engaged with the inner side 5 of the back wall and the inner side of the rear flange on the burner box bottom, and having openings provided therein in vertically spaced relation so that each attaching member receives one of the first and one of the last mentioned 10 bolts, whereby said attaching members are rigidly secured to the range in rigid relation to the cooking top.

2. A range construction as set forth in claim 1, wherein the upper end portions of said attaching 15 members have annularly projecting portions adjacent the cooking top to cover the slots provided therein.

3. A range construction as set forth in claim 1, wherein the back wall has openings provided 20 therein for extension of range members into the burner box above the burner box bottom, and wherein said attaching members are formed with the lower portions thereof in laterally offset relation to the upper portions for the purpose described, the lower portions being connected to the upper portions by intermediate portions 25 all extending in the same direction at an acute angle to the vertical to permit passage thereof through the slots in the cooking top. 30

4. In combination with a range having a cooking top portion, a counterbalanced lift cover for said cooking top portion comprising a sheet metal body of generally rectangular form having a hollow edge portion adapted to be hingedly connected to said cooking top portion, and semi-concealed combination hinge and counterbalancing means comprising an elongated hinge member disposed inside the hollow edge portion of said cover extending lengthwise thereof and providing 40 longitudinally spaced knuckles thereon, other hinge members having means for detachably securing the same to the cooking top portion and having end portions formed to provide knuckles adapted to be pivotally connected with the 45 knuckles on the first-mentioned hinge member inside the hollow edge portion of the cover, pintle means pivotally connecting the correlated knuckles, and one or more coiled torsion springs mounted within the hollow edge portion of the 50 cover on the pintle means, each with one end acting against the first-mentioned hinge member and the other end acting against one of the other hinge members tending to urge the cover to move upwardly. 55

5. A structure as set forth in claim 4, wherein one of the hinge members on the cooking top portion has a limiting stop projection provided on a knuckle thereof arranged to be engaged by a portion of the hinge member in the cover when the cover is raised to substantially vertical position.

6. A structure as set forth in claim 4, wherein one of the hinge members on the cooking top portion has a limiting stop projection provided on a 65 knuckle thereof arranged to be engaged by a portion of the hinge member in the cover when the cover is raised to substantially vertical position, and adjustable screw means on the last-mentioned hinge member adjustable toward and away 70 from the stop projection when the cover is in raised position, whereby to adjust the position of the cover in its limit position relative to the cooking top portion.

7. In combination with a range having a cook-

ing top portion, a counterbalanced lift cover for said cooking top portion comprising a sheet metal body of generally rectangular form having a hollow edge portion adapted to be hingedly connected to said cooking top portion, and semi-concealed hinge means for said cover comprising an elongated hinge member disposed inside the hollow edge portion of said cover extending lengthwise thereof and providing longitudinally spaced knuckles thereon, other hinge members having means for detachably securing the same to the cooking top portion and having end portions formed to provide knuckles adapted to be pivotally connected with the knuckles on the first-mentioned hinge member inside the hollow edge portion of the cover, and pintle means pivotally connecting the correlated knuckles.

8. A structure as set forth in claim 7, wherein one of the hinge members on the cooking top portion has a limiting stop projection provided on a knuckle thereof arranged to be engaged by a portion of the hinge member in the cover when the cover is raised to substantially vertical position.

25. 9. A structure as set forth in claim 7, wherein one of the hinge members on the cooking top portion has a limiting stop projection provided on a knuckle thereof arranged to be engaged by a portion of the hinge member in the cover when the cover is raised to substantially vertical position, and adjustable screw means on the last-mentioned hinge member adjustable toward and away from the stop projection when the cover is in raised position, whereby to adjust the position 35 of the cover in its limit position relative to the cooking top portion.

10. A counterbalanced hinge structure for a liftable cover or the like comprising an elongated substantially horizontal hinge member having a pair of longitudinally spaced knuckles provided thereon, a pair of other hinge members each having an attaching portion and having an end portion formed to provide spaced knuckles adapted to receive therebetween one of the knuckles on the aforesaid hinge member, pintle means for pivotally connecting the correlated knuckles and one or more coiled torsion springs mounted on the pintle means with one end abutting the first-mentioned hinge member and the other end abutting a knuckle on one of the other hinge members and tending normally to move the first-mentioned hinge member in one direction.

11. A hinge structure as set forth in claim 10, including a stop projection on one of the knuckles on one of the pair of hinge members arranged to be engaged by a portion of the first-mentioned

hinge member in a limit position thereof to prevent further relative movement in one direction.

12. A hinge structure as set forth in claim 10, including a stop projection on one of the knuckles on one of the pair of hinge members arranged to be engaged by a portion of the first-mentioned hinge member in a limit position thereof to prevent further relative movement in one direction, and adjustable screw means on said first-mentioned hinge member arranged to engage said stop projection to advance or retard the point at which the first-mentioned hinge member is stopped from further movement.

13. In combination with a range having a cooking top portion, a counterbalanced lift cover for said cooking top portion comprising a sheet metal body of generally rectangular form having an edge portion adapted to be hingedly connected to said cooking top portion, and combination hinge and counterbalancing means comprising an elongated hinge member secured to the inner side of the edge portion of said cover extending lengthwise thereof and providing longitudinally spaced knuckles thereon, other hinge members having means for detachably securing the same to the cooking top portion and having end portions formed to provide knuckles adapted to be pivotally connected with the knuckles on the first-mentioned hinge member, pintle means pivotally connecting the correlated knuckles, and one or more coiled torsion springs mounted on the pintle means each with one end acting against the first-mentioned hinge member and the other end acting against one of the other hinge members tending to urge the cover to move upwardly.

14. A structure as set forth in claim 13, wherein one of the hinge members on the cooking top portion has a limiting stop projection provided on a knuckle thereof arranged to be engaged by a portion of the hinge member on the cover when the cover is raised to substantially vertical position.

15. A structure as set forth in claim 13, wherein one of the hinge members on the cooking top portion has a limiting stop projection provided on a knuckle thereof arranged to be engaged by a portion of the hinge member on the cover when the cover is raised to substantially vertical position, and adjustable screw means on the last-mentioned hinge member adjustable toward and away from the stop projection when the cover is in raised position, whereby to adjust the position of the cover in its limit position relative to the cooking top portion.

STANLEY H. HOBSON. 55
